UNITED STATES PATENT OFFICE

TONY RESCH, OF ROCKWELL CITY, IOWA, ASSIGNOR OF ONE-FOURTH TO STANLEY A. FRICK, OF ROCKWELL CITY, IOWA

CLOSURE PACKING

Application filed April 15, 1931. Serial No. 530,413.

The invention relates to a closure packing, and more especially to a device for use on a door or the like for preventing the admission of air through an opening closed 5 thereby.

The primary object of the invention is the provision of a device of this character, wherein in the body thereof is freely resilient and contains a core which is expansible, so that on 10 the joining of the ends of the latter the device can be applied to a closure such as a door or the like whereby on shutting the same a fluid tight joint will be effected to exclude moisture and air from an enclosure through 15 the opening for the closure or door or the like.

Another object of the invention is the provision of a device of this character, wherein in the construction and arrangement of the 20 same permits its application to various structures, such as swinging window sash, carpet sweepers, vacuum cleaners, furniture or other articles and be effective as a bumper.

A further object of the invention is the provision of a device of this character, wherein in the construction thereof is novel in form and due to the elasticity of its body and core renders the use and application thereof extensive both as a packing and guard bumper. 25

A still further object of the invention is the provision of a device of this character, which is extremely simple in construction, thoroughly reliable and efficient in its purposes, strong, durable, neat and attractive in 30 appearance, and inexpensive to manufacture and install.

With these and other objects in view the invention consists in the features of construction, combination and arrangement of parts 40 as will be hereafter more fully described in the preferred embodiment, illustrated in the accompanying drawing which discloses the preferred embodiment of the invention, and pointed out in the claims hereunto appended.

In the accompanying drawing:—

Figure 1 is a fragmentary perspective view of a refrigerator of conventional type showing its door open and the device applied to the latter and constructed in accordance with 50 the invention.

Figure 2 is a fragmentary plan view on an enlarged scale of the device.

Figure 3 is a similar view with portions broken away to illustrate the core and the manner of connecting its ends together. 55

Similar reference characters indicate corresponding parts throughout the several views in the drawing.

Referring to the drawing in detail A designates a portion of the body or casing of a 60 refrigerator of any conventional type, B its front opening or entrance door way, and C the swinging door for this opening or door way. This type of article is shown in the drawing merely to illustrate one of many 65 applications of the closure packing or device constituting the present invention and as will be hereinafter more fully described.

The door C at its inner side is rabbeted as at D marginally thereof and within this 70 portion D is arranged the packing or device which comprises a body 5, of the required or desired length and made from sponge rubber impervious to air, water or moisture, the body in cross-section being preferably circular, although it may be of any other cross-sectional contour as the occasion may require. 75

The body 5 is formed with a central longitudinal bore 6 of the required size to accommodate a closely coiled retractile or expansion spring 7, the latter being co-extensive with the length of the body and the ends of this spring are joined together through the medium of eyes 8 formed from the terminals of the spring. 80

The length of the body 5 is slightly less than the extent of the rabbet D throughout the margin of the door C so that when the body is applied after the terminals of the spring 7 have been joined as shown in Figure 90 1 of the drawing the said spring will be under desired tension to hold the packing or device in place on the said door, the slightly separated ends 9 of the body can then be worked toward each other so as to be brought close together to avoid an open gap at these ends as will be apparent from Figures 2 and 3 of the drawing. 95

It should be apparent that when the door C is supplemented with the packing before de- 100

scribed and such packing is applied in the manner stated the door when closed will shut out moisture, air or fluid from gaining an entrance through the doorway B and in this manner a very desirable and efficient packing is established.

The packing hereinbefore described is also adaptable to carpet sweeper, vacuum cleaners, furniture and other articles to serve as a bumper. Also the packing is usable for weather stripping, especially with swinging window sashes and doors.

While there has been shown in the accompanying drawing a specific application of the packing or device it is to be clearly understood that the same is not to be construed as limited to such application or use, as the packing or device is equally adaptable for other applications and uses.

20 What is claimed is:—

1. The combination with an article having a movable closure, of a resilient body member thereon, and a coiled spring core within the body and joined at its ends to have said body member yieldably and snugly embrace the movable closure.

2. The combination with an article, of a sponge rubber body member thereon and yieldable in the direction of its length and transverse thereof, and a closely coiled tensioned spring core within the body and joined at its ends to have the body embrace said article and permitting movements independently of each other.

35

3. The combination of a sponge rubber body, and a closely coiled tensioned spring core mounted within the body and joined at its ends to effect the snug embracing of the body upon an article.

4. The combination of a sponge rubber body, and a closely coiled tensioned spring core mounted within the body and joined at its ends to effect the embracing of the body upon an article, the body being formed with a bore therethrough for accommodating the core to permit relative movements between the core and body.

5. The combination of a resilient body member, a closely coiled spring located approximately centrally within the body member, and means for securing the ends of the spring to effect a continuous core for the body member and the snug mounting of said body member upon an article of manufacture.

6. The combination of an elastic body of elongated formation having a bore therethrough, and a tensioned element yieldable in the line of its own axis and extending through the bore to cause said body to snugly embrace an article and constituting a sealing medium for a joint.

7. The combination of a tensioned member yieldable in the line of its own axis, and a relatively thick elastic body housing the member and one having relative yielding movement to the other.

In testimony whereof I affix my signature.
TONY RESCH.
